WORTHY CHANNING BUCKNAM, OF JERSEY CITY, NEW JERSEY, ASSIGNOR, BY MESNE ASSIGNMENTS, TO DAVIS AUTOMATIC EQUIPMENT CORPORATION, OF NEW YORK, N. Y., A CORPORATION OF NEW YORK.

COIN LOCK.

Application filed July 17, 1920. Serial No. 396,918.

To all whom it may concern:

Be it known that I, WORTHY C. BUCKNAM, a citizen of the United States, and a resident of Jersey City, in the county of Hudson and State of New Jersey, have invented a new and useful Coin Lock, of which the following is a specification.

This invention has to do with coin-controlled locks for public lockers. These locks are operable to lock the locker upon deposit of a coin; and the key is locked in the lock, against removal, when the locker is unlocked, and is removable only in the locked condition. A detent, blocking or locking device cooperating with the bolt to hold it in the retracted condition, or against movement from the unlocked to the locking position, is displaceable to permit locking, through the agency of the coin. When the user wishes to take out his belongings checked in the locker he does so by use of the key, and the detent then acts to prevent relocking of the door and to lock the key in place, until another coin is deposited. There is necessarily a gap between the door and frame, or between the bolt and its keeper in the unlocked condition, which will vary somewhat in different lockers; and through accident or design the bolt may be retracted sufficiently to clear its keeper and the door opened without the bolt being caught. In this way the locker can be used again without introducing another coin, or, which is more serious, the locker may be left open with the bolt projected and the key removable, so that the key may be lost or stolen, loss of the key necessitating replacement of the lock, or, if this should not occur, an intending user of the locker depositing a coin while the bolt is protracted with the door standing open would lose his coin. The object of the invention is to overcome these difficulties; which is accomplished by the provision of means whereby the lock is caught against relocking when the bolt is partially retracted; hence, if at this point the door can be opened, the lock cannot be relocked without deposit of another coin, nor can the key be removed by a mischievous person. In the simple and preferred embodiment of the invention, the detent is formed with primary and secondary holding shoulders opposing locking movement of the bolt, the primary shoulder holding or confining the bolt in the proper

unlocked condition, and the secondary shoulder being positioned to restrain it when partially retracted.

The invention is more particularly concerned with a type of lock in which the bolt is shot by a spring and held by direct engagement with a detent, which is displaceable by a knob-operated coin-mover, and in which the bolt is retracted by a key-operated key-cylinder, as more fully set forth herein-after; but various modifications will suggest themselves to the mechanic skilled in the art.

In the accompanying drawings forming a part hereof:

Figure 1 is a front elevation of the lock, in the unlocked condition;

Fig. 2 is a rear elevation thereof, indicating in dotted lines a coin just seated in the pocket of the coin-disk;

Fig. 3 is a rear elevation illustrating the locking condition, the cover of the coin-disk casing being removed, and the coin having just displaced the detent and being about to drop out of the coin-disk, as indicated in dotted lines; and

Fig. 4 is a rear elevation illustrating the bolt caught in partly retracted condition.

The general lock construction in which the present invention is shown embodied forms the subject-matter of a separate application, Serial No. 397,118, filed July 17, 1920, in which the present applicant is joint inventor with another.

The front plate or escutcheon 1 has a knob 2, a coin-entrance 3 and the key-slot end of a key-cylinder 4 on its outer side. This key-cylinder and its cylinder-casing 5 constitute a well-known form of lock unit, containing tumbler arrangements whereby the key can be removed in the locking condition only, and is locked in the lock by the tumblers when the lock is open. These matters being familiar require no illustration.

A swinging bolt 8 is pivoted at 11, and is projected by a spring 17. The bit 14 of the key-cylinder cooperates with a recess 100 or socket 15 in the rear portion of the bolt. A bell-crank detent is pivoted at 19 and its rearwardly extending arm is formed with a primary holding shoulder 21, which cooperates with a projection 23 on the bolt to hold the latter in its fully retracted condition, the detent having a spring 24 whereby it engages automatically.

The contact extremity of the downwardly extending arm 26 of the detent is arranged to be encountered by a coin *a* carried by a rotary coin-disk 30 having an eccentric coin-pocket 31. The disk is connected to the knob 2 on the outside, and receives the coin from a coin-drop 29 on the inside leading from the coin-entrance 3.

When the detent is displaced through the deposit of a coin and the turning of the knob, 10 the bolt is freed to move to its locking or projected position. The key-cylinder being connected with the bolt is also moved to the position in which the key can be removed by the user, to constitute his check. When he 15 wishes to regain his property he inserts the key and turns it in the unlocking direction, thereby retracting the bolt, which is caught and held by the detent, the key being thereby 20 locked in the cylinder until the next checking operation.

According to the present invention, secondary holding or detent means is provided which engages with the lock mechanism before the bolt is completely retracted. This is 25 most simply accomplished by forming the main detent, such as the detent 18, with a shoulder 21^a slightly in advance of the shoulder 21. This shoulder engages the bolt- 30 projection 23 when the bolt is partly retracted, and prevents it returning or being returned in the locking direction, without the deposit of another coin. Thus even though it may be possible to open the door 35 of the locker with the bolt in the incompletely retracted condition of Fig. 4, the key will not be left free in the lock, nor can the user obtain a second checking service on the same coin. The invention is not necessarily

limited to two shoulders or successive de- 40 tents, since more may be employed, and the cooperating elements may, of course, be reversed.

The invention also prevents false opera- 45 tion of the counter 7, with which these locks are provided, and which in the particular construction illustrated is operated from the detent through a link 22^a.

What I claim as new is:

1. In a coin-controlled lock for public 50 lockers, the combination of a bolt, a detent preventing movement of the bolt from fully retracted to locking position, coin-controlled means for freeing the bolt from said detent so that the bolt may be projected, key mech- 55 anism arranged to retract the bolt, said key mechanism permitting removal of the key only in the locking condition of the bolt, and means whereby the bolt is automatically caught against relocking when the bolt is 60 only partially retracted, in order that loss of the key may be prevented.

2. In a coin-controlled lock for public 65 lockers, the combination of a spring-shot bolt, a spring-actuated detent, having a plu- 70 rality of holding shoulders adapted to engage and hold the bolt successively against locking movement under the action of its spring, said detent normally restraining the bolt against movement under the action of its spring, a knob-operated coin-mover for displacing said detent, and key-operated means for retracting the bolt, said key-operated means being adapted to permit re- 75 moval of the key only in the locking condition of the bolt.

WORTHY CHANNING BUCKNAM.
